UNITED STATES PATENT OFFICE.

WILLIAM C. BLASKE, OF CHICAGO, ILLINOIS, ASSIGNOR, BY MESNE ASSIGNMENTS, TO
HEAT SAVER COMPANY, OF CHICAGO, ILLINOIS, A CORPORATION.

FUEL-SAVING DEVICE.

1,116,224.

Specification of Letters Patent.

Patented Nov. 3, 1914.

Application filed December 1, 1913. Serial No. 804,058.

To all whom it may concern:

Be it known that I, WILLIAM C. BLASKE, a citizen of the United States, residing at Chicago, in the county of Cook and State 5 of Illinois, have invented new and useful Improvements in Fuel-Saving Devices, of which the following is a specification.

The invention relates to new and useful 10 improvements in fuel saving-devices for delivering to the highly heated combustible gases evolved from the fire, a stream of preheated air having a sufficient heat to produce the combustion of gases.

The invention has for an object to provide 15 a fuel saving apparatus of this character which may be applied to the stove pipe of a stove burning anthracite coal to prevent the gases escaping from the stove through the air inlet holes thereof which will 20 retard the air before mixing with the gases arising from the combustion of the fuel.

Another object of the invention is to provide 25 a fuel saving device of this character wherein the cold air will be permitted to pass freely therethrough, but will be retarded sufficiently to prevent a draft within the stove pipe.

Another object of the invention is to provide 30 an air preheating chamber for devices of this character which will have a greater radiating surface, thereby permitting the air to be thoroughly preheated before mixing with the gases arising from the combustion of the fuel.

With the above and other objects in view 35 the invention may be said to consist of the novel features of construction, combination, formation and arrangement of parts as will be hereinafter more fully described and particularly pointed out in the appended claim.

In the accompanying drawings: Figure 1 is a vertical sectional view embodying my invention, and, Fig. 2 is a horizontal section through the same taken on the line 45 2—2 of Fig. 1.

Reference now being had to the accompanying drawings whereby like and corresponding parts will be designated by similar reference characters throughout the several views, the numeral 1 indicates a cylindrical tube forming substantially one section of a stove pipe and having the adjacent sections 2 connected thereto in the usual manner. Encircling the tube 1 is an outer 55 cylindrical casing 3 forming therebetween

the air preheating chamber. A conical section 4 is connected to the casing 3 by means of the beaded connection 5 at its upper end and its lower end is connected to the tube 1 by any suitable means or by rivets 6 as 60 shown. For closing the upper end of the air preheating chamber a circular plate 7 is provided, being connected to the casing 3 by means of the beaded connection 8 and to the tubing 1 by means of the angular plate 9. 65 Supported within the tube 1 is the usual damper 10 being rotatably mounted upon the shaft 11 which is adapted to be operated through the lever 12 in the usual manner.

The lower wall 4 of the air preheating 70 chamber has stamped therein a plurality of openings 14 which form a communication between the air preheating chamber and the atmosphere. The metal indicated by the numeral 15 being cut away to form the openings 14 acts as a baffle plate for retarding the air when entering the preheating chamber. A plurality of small openings 16 are formed within the tubing 1 and communicate with the lower end of the air preheat- 75 ing chamber, whereby the preheated air may enter the smoke stack in small streams.

In using such devices with stoves burning anthracite coal it has been found that the gases in the coals escaped through the air 80 preheating chamber and then into the atmosphere which makes the device inoperative. To overcome this objection a cylindrical partition 17 is provided within the air preheating chamber; having its lower end 85 secured in any preferred or well known manner or by rivets 18, as shown, to the lower wall 4 of the air preheating chamber. The upper end of the partition 17 is held in spaced relation from the wall 7 of the chamber whereby the air coming in through the openings 14 as indicated by the arrows, will pass up through the chamber then over the partition 17 where it again will travel down through the chamber and thence pass 90 through the openings 16 in its quiescent state where the same will be permitted to mix with the gases arising from the combustion chamber. As the air within the preheating chamber is permitted to first travel up and thence down within the chamber it will be thoroughly preheated before entering the chimney 1, thereby the device renders a larger heating surface for the air. 95

Leading to the upper end of the tube 1 110

is an overdraft casing 19 having a door 20 hinged thereto whereby a suitable overdraft may be provided for the device.

I claim:

- 5 In a device of the character described, a flue section having the same diameter throughout, a casing concentric with the flue section and spaced therefrom, a plate connecting the upper end of the casing with the flue section, a frusto conical section connecting the lower end of the casing with the flue section forming an air pre-heating chamber between the flue section and the casing, a partition concentric with the flue
- 10 section projecting within the air pre-heating chamber, the lower end of the partition being secured adjacent the medial portion of the inner wall of the conical section of the casing, the upper end of the partition
- 15

being held in spaced relation with the plate 20 connecting the upper end of the casing with the flue section, the frusto conical section of the casing having a plurality of openings formed therein, baffle plates formed integral with said conical section and projecting 25 over said openings, and the flue section having a plurality of openings formed therein forming a means of communication between the lower end of the air pre-heating chamber and the flue for the purpose set forth.

In witness whereof, I hereunto subscribe my name to this specification in the presence of two witnesses.

WILLIAM C. BLASKE.
